UNITED STATES PATENT OFFICE

2,445,201

CIGARETTE DISPENSER

Charles C. Anderson, Dayton, Ohio

Application May 13, 1947, Serial No. 747,704

1 Claim. (Cl. 312—78)

1

The present invention relates to new and useful improvements in cigarette dispensing devices, and more particularly to a portable device of this character adapted for placing on a table or other article of furniture and including means for manually dispensing cigarettes singly therefrom.

More specifically, the invention embodies the provision of a portable cabinet structure including a base having sliding drawers mounted therein for containing packages of cigarettes or other smoker's articles and mounting a cigarette container on top of the base for holding a plurality of loose cigarettes and providing a manually operated dispensing device working in the container to dispense cigarettes singly therefrom.

An important object of the present invention is to provide a device of this character of simple and practical construction, which is neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the device with parts broken away and shown in section;

Figure 2 is a vertical sectional view taken on a line 2—2 of Figure 1;

Figure 3 is an enlarged fragmentary sectional view taken substantially on a line 3—3 of Figure 2 and with parts of the base broken away and shown in section;

Figure 4 is a fragmentary transverse sectional view taken substantially on a line 4—4 of Figure 2; and

Figure 5 is a vertical sectional view taken on a line 5—5 of Figure 1.

Referring now to the drawings in detail wherein, for the purpose of illustration, I have disclosed a preferred embodiment of the present invention, the numeral 5 designates the base portion of a portable cabinet structure, the base being hollow and including a bottom 6, top 7 and side walls 8. The side walls have openings 9 therein for receiving drawers 10 having knobs 11 to slide the drawers into and out of the base through the openings 9 thereof.

Mounted on the top 7 of the base, and suitably secured thereto, is a substantially rectangular housing or container 12 having a false bottom 13 therein provided with sloping sides of substantial trough-shaped construction and having an

opening 14 at the bottom of the trough. The ends of the container 12 are formed with vertical grooves 15 in which the end edges of a vertically slidable cigarette dispensing member 16 are engaged. The dispensing member 16 works through the opening 14 of the trough and also works through an opening 17 in the top 7 of the base.

An inverted U-shaped bracket 18 is secured to the under side of the top 7 and to which the intermediate portion of a lever 19 is pivotally supported by a wire hanger 20 which is pivoted both to the bracket 18 and to the lever 19 to provide for a swinging as well as a pivotal movement of the lever. One end of the lever projects outwardly through a vertical slot 21 in one side wall of the base and the inner end of the lever is bifurcated, as shown at 22, to straddle the lower edge of the dispensing member 16, the bifurcated end of the lever being pivoted to the central lower edge of the dispensing member by a pin 23.

The dispensing member 16 is normally held in a raised position in the container 12 by means of a coil spring 24 attached at one end to the bottom 6 of the base and having its other end attached to the lever 19 at a point outwardly of the hanger 20.

The dispensing member is lowered for receiving a cigarette in a longitudinally extending trough 27 in the upper edge of the member by lifting the outer end of the lever 19 upwardly, which causes the hanger 20 to swing inwardly toward the dispensing member and upwardly into the position shown by dotted lines in Fig. 2 to compensate for the variation in the vertical sliding movement of the dispensing member and the arc of the pivotal movement of the lever. The raising of the outer end of lever 19 increases the tension on spring 24 which is moved toward a parallel relation with the lever to exert a longitudinal pulling force on the lever which causes a canting effect on the dispensing member to bind the latter in the grooves 15 and thus holds the dispensing member in its lowered position until the outer end of the lever is again lowered to dispense the cigarette.

The container 12 is constructed in the form of a miniature house and the top 25 represents a peaked roof with the opening 26 at its ridge. Each sloping side of the roof is provided with a slot 29 for filling the container with cigarettes, the slots being closed by sliding closures 30. At one end of the container is an imitation chimney 31.

What I claim as new is:

A cigarette dispenser comprising a cigarette container and a supporting base therefor, a vertically slidable dispensing member working in the

container to raise cigarettes singly to the top of the container, a lever pivotally and swingably carried by the base and connected at one end to said member for actuating the latter, and a coil spring connected to the lever to hold the dispensing member in a raised position, said spring being arranged to exert its influence longitudinally on the lever when the dispensing member is in its lowered position to bind the member against the sides of the container and also to hold the member in its lowered position.

CHARLES C. ANDERSON.
